(57) **CLAIM**

The ornamental design for a motorcycle, as shown and described.

DESCRIPTION

FIG. 1 is a top, front, and left side perspective view of a motorcycle embodying our new design;
FIG. 2 is a bottom, rear, and right side perspective view thereof;

FIG. 3 is a right side elevation view thereof;

FIG. 4 is a left side elevation view thereof;

FIG. 5 is a bottom plan view thereof;

FIG. 6 is a top plan view thereof;

FIG. 7 is a rear elevation view thereof;

FIG. 8 is a front elevation view thereof;

FIG. 9 is an enlarged and partial perspective view of area 9 in FIG. 1;

FIG. 10 is an enlarged and partial perspective view of area 10 in FIG. 1;

FIG. 11 is an enlarged and partial perspective view of area 11 in FIG. 1;

FIG. 12 is an enlarged and partial perspective view of area 12 in FIG. 2;

FIG. 13 is an enlarged and partial perspective view of area 13 in FIG. 2;

FIG. 14 is an enlarged and partial perspective view of area 14 in FIG. 2;

FIG. 15 is an enlarged and partial perspective view of area 15 in FIG. 2; and,

FIG. 16 is an enlarged and partial perspective view of area 16 in FIG. 2.

The broken lines shown in the drawings illustrate portions of the motorcycle that form no part of the claimed design.

1 Claim, 16 Drawing Sheets
